ROTARY ELECTRIC SWITCH

Alvin W. Krieger, Milwaukee, Wis., assignor to
 Cutler-Hammer, Inc., Milwaukee, Wis., a corporation of Delaware

Application March 10, 1949, Serial No. 80,616

14 Claims. (Cl. 200—66)

1 This invention relates to improvements in rotary electric switches.

A primary objective of the invention is to improve the construction and the operating characteristics of switches of the aforementioned character.

Another object is to minimize the number of different parts required to produce a rotary electric switch.

Another object is to provide unusual flexibility in the manner in which the switch parts may be assembled, whereby a large variety of desired circuit controlling characteristics may be attained.

Another object is to provide parts of simple form which may be combined to form switches of either single-pole or multi-pole type.

Another object is to provide novel snap action means which permit rotation in either direction selectively.

Another object is to provide combined contact and terminal members of novel form, the terminal portions of which are exposed and readily accessible at the exterior of the switch base.

Another object is to provide a novel form of movable contact carrier.

Another object is to provide an insulating base having recesses of novel form therein to house and support combined stationary contact and terminal members.

Another object is to provide a novel form of insulating base which in cooperation with a contact carrier effectively snuffs out any arcing that may occur at the contacts.

Various other objects and advantages of the invention will hereinafter appear.

The accompanying drawings illustrate certain embodiments of the invention which will now be described, it being understood that the embodiments illustrated are susceptible of modification within the scope of the appended claims.

In the drawings,

Figure 1 is a side elevation of a single pole switch (actual size) capable of providing from two to six operative positions.

Fig. 2 is a top plan view of the switch (actual size), the mounting nuts being omitted for sake of clarity.

Fig. 3 is an enlarged vertical section taken on line 3—3 of Fig. 2 with the snap action operating mechanism being shown in elevation and the switch parts in an "on" position.

Fig. 4 is an enlarged vertical section taken on line 4—4 of Fig. 2, but showing the addition of another pole, the contacts of both poles being shown in an "off" position, the movable contact

of the upper pole being shown in section and that of the lower pole in elevation.

Fig. 5 is a horizontal section taken on line 5—5 of Fig. 4 showing a stop lever in one of its extreme positions.

Fig. 6 is a horizontal section taken on line 6—6 of Fig. 4, the dotted line representation showing a second position of the switch parts.

Fig. 7 is a horizontal section taken on line 7—7 of Fig. 4.

Fig. 8 is a horizontal section taken on the broken line 8—8 of Fig. 4 showing two combined stationary contact and terminal members and a movable contact carrier, the full line representation illustrating the switch parts in an "off" position, the dotted lines showing the switch parts in an "on" position.

Fig. 9 is a horizontal section taken on line 9—9 of Fig. 4 with the contact carrier removed, but with one position of a movable contact illustrated in dotted lines.

Fig. 10 is a horizontal section taken on line 10—10 of Fig. 4 but with the contact carrier removed and showing two combined stationary contact terminal members and three insulating plugs in position.

Fig. 11 is a detail plan view of a stop lever for a five position switch illustrating its relationship to the operating shaft and stop lug.

Fig. 12 is a horizontal section similar to that of Fig. 9 but showing the contact carrier, additional movable contacts and combined stationary contact terminal members, and a stationary contact ring with an additional terminal lug.

Fig. 13 is a horizontal section similar to that of Fig. 9 illustrating a split stationary contact ring, each segment thereof having a terminal member, the dotted lines representing relative positions of a plurality of movable contacts.

Referring to the accompanying drawings, there is illustrated therein a switch embodying the invention having a maximum of six positions, though it is to be understood that switches having a greater number of positions might be afforded by suitable enlargement of the switch bases. Similarly, while switches having only one and two poles are illustrated, it is to be understood that a greater number of poles may be afforded by addition of extra base sections as will hereinafter appear.

In the drawings the reference numeral 15 designates a preferably cylindrical metal operating shaft for the switch having a flat surface 15^a at the upper end thereof for accommodating a knob (not shown). As will be apparent the length of

shaft 15 will depend on the number of switch poles provided as indicated, for example, by comparison of Figs. 3 and 4. Shaft 15 is rotatably supported by an externally threaded bushing 16 (Fig. 4) having a reduced lower end for insertion through a centrally located opening in a substantially circular switch cover member 17, said bushing being upset over the inner surface of said cover member 17 as at 16^a to rigidly attach the same thereto. Bushing 16 is further provided with a vertically aligned peripheral notch 16^b for interlocking with an upstanding lug 17^a formed integrally with cover member 17, said interlock preventing relative rotary displacement of the two members. Threaded on to bushing 16 are two nuts 18 and 19, a washer 20, and a locking ring 21 for one-hole mounting of the switch in a well known manner. Shaft 15 is peripherally grooved as at 15^b to accommodate a split washer 22 adapted to prevent downward displacement of shaft 15 relative to bushing 16.

As best illustrated in Figs. 5 and 6, the portion of shaft 15 extending immediately downward from the bottom end of bushing 16 is flattened on opposite sides thereof as at 15^c for insertion, in the order stated, through correspondingly shaped openings in a stop lever 23 (when employed), an eccentric cam member 24, and a lever member 25 each to be hereinafter more particularly described, said three last mentioned members each being rigidly attached to shaft 15 by staking thereof as at 15^e (Fig. 4), the remaining portion 15^d of shaft 15 extending downwardly therefrom being of substantially reduced cylindrical contour.

Stop lever 23 may be a flat metal member of peripheral contour best illustrated in Fig. 5 having an arcuate portion 23^a the ends of which are adapted to engage a lug 17^b formed integrally with and depending from cover member 17, thus to limit the rotation of shaft 15. As will be apparent the permissible degree of rotation of shaft 15, hence the number of operative switch positions, is determined by the degree of arc afforded by said portion 23^a, that shown in Fig. 5 affording for the switch illustrated three operative positions. It will be obvious to those skilled in the art that omission of stop lever 23 entirely would permit 360° rotation of shaft 15, hence affording in the switch illustrated, six operative positions, while for example, formation of stop lever 23 as shown at 123 in Fig. 11 would afford five operative positions, the relationship of those positions to stop lug 17^b being also shown in Fig. 11.

As best shown in Fig. 6, eccentric cam 24 is a flat substantially circular metal member having a peripheral notch 24^a for accommodating the flattened portion of shaft 15 is hereinbefore described, the center of cam 24 being laterally displaced with reference to the axis of rotation of shaft 15 as will be apparent.

Surrounding cam 24 with a close sliding fit and in the same plane therewith is a flat annular portion 26^a of a lever member 26 adapted to rotate about said cam 24 as a center, said member 26 also having an integrally formed depending portion 26^b best illustrated in Figs. 3 and 4.

Lever member 25 (Fig. 6) comprises a flat substantially circular portion 25^a rigidly attached to shaft 15 immediately below eccentric cam 24 as hereinbefore described, a wing-like arcuate extension 25^b integrally formed with and lying in the same plane as portion 25^a, and an integrally formed depending lug 25^c best shown in Figs. 3

and 4. The aforementioned arcuate extension 25^b provides a stop to cooperate with depending portion 26^b to limit rotation of lever member 26 in either direction about eccentric cam 24 as a center as hereinbefore described.

Slidably fitted about the aforementioned reduced cylindrical portion 15^d of shaft 15 (Fig. 4) and extending downwardly from the three aforementioned rigidly attached members 23, 24 and 25 substantially the entire length of said portion 15^d is a metal bushing 27 preferably square in transverse section. Loosely fitted about the upper end of said bushing 27 is an annular metal bushing 28 having flanges 28^a and 28^b at opposite ends thereof to retain in place a relatively heavy helical spring 29 loosely fitted about said bushing 28.

As best shown in Fig. 7, a flat metal member 30 of substantially the contour shown and having a square opening for insertion therethrough of bushing 27 with a close fit and consequent interlocking therewith is mounted to underlie the flanged end 28^b of bushing 28. Said member 30 is slotted at one end thereof as at 30^a to slidably accommodate a lug 26^c formed integrally with and extending downwardly from depending portion 26^b of lever 26. As best shown in Figs. 3 and 4, the opposite end of member 30 is provided with an integrally formed upstanding lug portion 30^b adapted to extend upwardly between bushing 28 and depending lug 25^c of lever 26. As best shown in Figs. 3 and 7, the opposite ends 29^a, 29^b of spring 29 are brought out on opposite sides of lugs 25^c and 30^b thus tending to keep those two members in alignment.

The parts described immediately above when combined with an annular metal stop plate 31 to be hereinafter described, form a snap action mechanism adapted to be housed in a substantially circular centrally located recess 32^a in a substantially circular molded insulating base section 32 best shown in Figs. 3 and 4, the bottom wall of said recess 32^a having a circular central opening 32^b (Figs. 3 and 4) through which shaft portion 15^d and its bushing 27 extend with clearance for rotation. Stop plate 31 overlies the top surface of said base section 32, it being interposed between said top surface and a flanged portion 17^c of cover member 17. The parts are held in the aforescribed relation by screws 33 preferably three in number (Figs. 1 and 2) inserted upwardly through aligned openings in base sections to be hereinafter described, base section 32 and stop plate 31, and threaded into flange portion 17^c of cover 17, said screws preferably being upset as at 33^a over the top surface of flange 17^c, the length of said screws, as will be apparent, depending on the number of base sections employed.

As best shown in Fig. 6, annular stop plate 31 is provided on the inner periphery thereof with a series of equally spaced notches 31^a (six in number in the switch illustrated) each being adapted to receive and temporarily hold portion 26^b of lever 26 against rotary displacement on operation of the snap action mechanism, the aforescribed relation affording a switch with a maximum of six operative positions.

The operation of the aforescribed snap action mechanism is as follows: Assuming the parts to be in the position shown in full lines in Fig. 6, with portion 26^b of lever 26 projected into a notch 31^a to lock said lever and interconnected member 30 against rotation, clockwise rotation of shaft 15 within the limits afforded by stop plate 23 and stop lug 17^b results in clockwise rotation of lever

25 and its depending lug 25^a forcing end 28^a of spring 28 in clockwise direction, the other end of spring 29 being restrained by lug 30^b on locked member 30. Simultaneously eccentric cam 24 is given a clockwise movement about a point defined by the center of shaft 15 and this rotation of cam 24 results in a gradual movement of portion 26^b inwardly toward the center of the switch and out of engagement with the aforementioned notch 31^a while lug 26^c of depending portion 26^b moves inwardly in slot 30^a of lever 30. Sufficient clockwise movement of the aforementioned parts having taken place, portion 26^b is moved free of the restraining notch 31^a, and spring 29 snaps member 30 rapidly in a clockwise direction and member 30 in turn snaps member 26 in a clockwise direction simultaneously causing bushing 27, to which member 30 is interlocked as hereinbefore described, to rotate rapidly on portion 15^d of shaft 15 as an axis. Continued rotation of lever 26 about cam 24 causes portion 26^b to be simultaneously moved outwardly to engage the next adjacent notch 31^a in stop plate 31, this preventing any further rotation of the parts. Thus the aforescribed operation has advanced lever 26 in rotary motion equal to the angular distance of one notch in stop plate 31 (60° in the switch illustrated) to the position indicated by the dotted lines in Fig. 6 and a rapid snap rotary movement of an equal number of degrees has been imparted to bushing 27.

As will be apparent, rotation of shaft 15 in a counter-clockwise direction causes the above described parts to respond in a similar manner resulting in snap movement of bushing 27 in counter-clockwise rotation, the aforescribed operative characteristics thus affording a switch actuating means permitting snap action in either direction of rotation.

As best shown in Figs. 3, 4 and 8, shaft portion 15^d and its bushing 27 are inserted with a sliding fit through a preferably square centrally located opening (Fig. 8) in a relatively thick substantially cylindrical body portion 34^a of a molded insulating contact carrier 34 to rotate the same as a function of the snap movements imparted to bushing 27 as hereinbefore described. Said carrier 34 is provided with a relatively thin integrally formed peripheral flange or lateral extension 34^b located intermediate the ends of said cylindrical portion 34^a and with a plurality (six in the switch illustrated) of substantially rectangular openings 34^c extending through said carrier and through both the body portion and flange of said carrier. Openings 34^c are equally spaced from and about the center of said contact carrier 34 extending radially beyond the periphery of the body portion 34^a into the flange portion 34^b as aforeindicated. In any or all of said openings 34^c is positioned a U-shaped bridging contactor 35 (Fig. 8). As best shown in Figs. 3 and 4, each of said bridging contactors has its side walls slotted at 35^a to provide lateral clearance for and to aid in the positioning of a helical spring 36 located between its side walls. Said springs 36 are placed so that one end thereof abuts the inner end wall of opening 34^c, while the other end engages the inner surface of the bottom of U-shaped bridging contactor 35 thus to bias said bridging contactor outwardly so that it projects beyond the periphery of cylindrical portion 34^a with its ends exposed above and below flange 34^b.

As best shown in Figs. 3 and 4, there is provided a housing for each contact carrier 34 as well as for stationary contacts to be hereinafter described,

each housing comprising matching insulating sections, and the base section 32 forming such a housing section.

Where a single pole switch is desired (Fig. 3) the base section 32 is utilized as the top of the housing and a bottom section designated generally by the reference numeral 37 is provided. Where a switch of two or more poles is desired (Fig. 4) one or more intermediate base sections designated generally by the numeral 40, one for each additional pole, may be interposed between said base sections 32 and 37, each such interposed base section to contain a contact carrier of the type above described. The upper surface of each intermediate section 40 may be and preferably is formed substantially identically to the upper surface of bottom section 37, while the bottom surface of each such intermediate base section may be and preferably is formed substantially identically to the bottom surface of base section 32, all as hereinafter more particularly described, thus to provide a structure whereby a varying number of poles may be provided without need of specially designed additional housing parts.

As best illustrated in Figs. 3 and 10, the bottom surface of base section 32 is provided with a polygonal central portion 32^c extending downwardly a relatively small distance therefrom, said central portion being penetrated by opening 32^b for insertion therethrough of shaft portion 15^d and its bushing 27 as hereinbefore described. Said central portion 32^c is of substantially the same diameter as cylindrical portion 34^a of contact carrier 34 and is adapted to function as a bearing surface for the latter. Also the bottom surface of base section 32 is provided with a plurality of integrally formed depending portions 32^d and 32^e of the contour in horizontal section best shown in Fig. 10, said portions 32^e being enlarged throughout the depth of said base section 32 and each having an opening for insertion therethrough of one of the screws 33 as hereinbefore described. Portions 32^d and 32^e are spaced equidistantly about the periphery of the bottom surface of base section 32 to provide a castellated structure (Fig. 1), the inner edges of said portions being so spaced from the center as to accommodate the flanged portion 34^b of contact carrier 34 when in assembled relation (Fig. 8). Formed integrally with each of said portions 32^d, 32^e and with the bottom surface of base section 32 are a plurality of shoulders 32^f of the contour in horizontal section best shown in Fig. 10, said shoulders projecting inwardly from portions 32^d, 32^e as shown and projecting downwardly from the bottom surface of base section 32 a distance intermediate that of the lower surfaces of central portion 32^c and portions 32^d, 32^e, said shoulders 32^f being adapted to engage flange 34^b of contact carrier 34.

The aforescribed structure provides base 32 with a plurality of peripheral openings or windows as illustrated, for example, at 32^g (Fig. 10), in each of which may be positioned a U-shaped combined stationary contact and terminal member 38 (Fig. 3), the number provided varying with the number of operative switch positions desired. As best shown in Fig. 10, said members 38 are preferably of sufficient width to fit snugly within openings 32^g, the bottom 38^a of said U-shaped member having set back edges to provide notches to accommodate extensions 32^h extending laterally from each of said shoulders 32^f thereby to prevent outward displacement of said members 38. The outer arms 38^b of

members 38 are each preferably provided with a binding screw 39^c for attachment of circuit wires; while, as best illustrated in Figs. 3 and 8, the inner arms 38^d extend downwardly a distance sufficient to permit them to engage one end of a movable contact 35 hereinbefore described.

In the event that certain of the aforescribed peripheral openings 32^c are unused, a flat insulating member or plug 39 may be positioned therein to prevent dust or other foreign material from entering the switch. Said insulating members 39 are of sufficient width to close off the aforementioned openings 32^c (Fig. 10) and are adapted to abut the outer side edges of the aforesaid extensions 32^b to prevent displacement inwardly, while outward displacement of said insulating members is prevented by an interlock afforded by an upwardly extending tongue 39^a (Fig. 3) projecting into a substantially rectangular recess 32ⁱ (Figs. 4 and 10) formed in the bottom surface of base section 32 and located with respect to openings 32^c as best illustrated in Fig. 10. A second tongue-like extension 39^b is provided on the opposite end of member 39 to cooperate in a like manner with a recess 37^b in the next adjacent base section as will herein-after be described.

Base section 37 (Figs. 3 and 4) is of substantially circular contour in horizontal section (Fig. 9) and has a substantially circular centrally located recess 37^a (Fig. 3) extending downwardly from the top plane thereof. Extending radially from said central recess 37^a are a plurality of smaller recesses 37^b (six in number in the switch illustrated) of the contour best illustrated in Fig. 9, the side walls of said recesses being formed by inwardly extending portions 37^c, 37^d formed integrally with the base section 37. Portions 37^c and 37^d are of the relative size and shape best illustrated in Fig. 9, each having a depressed shoulder 37^e of the contour in horizontal section shown in Fig. 9. As illustrated in Fig. 8, said portions 37^c, 37^d may be alined with depending portions 32^d, 32^e of base section 32 respectively and are adapted to mate therewith thus forming the openings or windows 32^c as shown in Fig. 1, recesses 37^b being alined therewith. As best illustrated in Fig. 12, the inner edges of said portions 37^c, 37^d are so spaced from the center of the base as to provide clearance for the flange 34^b of contact carrier 34 when in assembled relation, while, as best illustrated in Fig. 3, the upper surfaces of shoulders 37^e are adapted to cooperate with shoulders 32^f depending from base section 32 to form a guideway for said flange portion 34^b, and the inner edges of said portions 37^e are so spaced from the center of base section 37 as to provide clearance for cylindrical body portion 34^a of contact carrier 34.

The bottom wall of recess 37^a may be provided with a centrally located substantially circular portion 37^f (Fig. 9) formed integrally therewith and extending upwardly therefrom. As best illustrated in Figs. 3 and 4, said portion 37^f is adapted to provide a bearing surface for cylindrical body portion 34^a of contact carrier 34 and the lower end of bushing 27, a centrally located opening 37^g being provided for insertion therethrough with a sliding fit of the lower end of shaft portion 15^d.

A flat annular metal collector ring 41 (Fig. 9) of good electrical conductivity is provided for positioning within recess 37^a against the bottom wall thereof and fitted around said circular por-

tion 37^f. The outer periphery of said collector ring 41 is provided with a plurality of equally spaced integrally formed upturned portions 41^a (Fig. 3) to serve as stationary contacts as will hereinafter be described, said portions 41^a projecting radially a sufficient distance into recesses 37^b (Fig. 9) to cause the side edges thereof to interlock with the side edges of shoulders 37^e, thus to prevent rotary displacement of said collector ring 41. In lieu of a stationary contact member 41^a, collector ring 41 is provided at one point on the periphery thereof with an integrally formed upturned terminal member 41^b (Fig. 9) extending outwardly into recess 37^b and upwardly (Fig. 4) a sufficient distance to permit a binding screw 41^c threaded therein to project outwardly for access from the exterior of the switch through window or opening 32^c hereinbefore described. As best shown in Figs. 4 and 8, the terminal screw portion 41^d of said terminal member 41^b is of sufficient size to close off window 32^c, the side edges of said portion 41^d overlapping the top surface of base section 37 while the inner surface of said portion abuts the side edges of portions 32^b of base section 32. The upper end of said portion 41^d is also provided with an upwardly extending tongue 41^e (Fig. 9) for insertion into recess 32ⁱ of base section 32, (Fig. 4), the foregoing relationships preventing displacement of said terminal member 41^b in any direction.

An annular insulating washer 42 surrounding portion 37^f of base 37 may be interposed between collector ring 41 and contact carrier 34 as shown in Figs. 3 and 4.

As illustrated in Fig. 3, stationary contact portions 41^a are each positioned in alinement and in spaced opposed relation to inner arms 38^d of such combined stationary contact and terminal members 38 as may be employed, the outer arms 38^b of each of said U-shaped members 38 having a depending tongue portion 38^e (Fig. 10) extending downwardly into recesses 37^b for interlocking with base section 37 (Fig. 3) to aid in maintaining such positioning and spacing when the aforementioned parts are in assembled relation. Said stationary contacts 38^d and 41^a are adapted to be bridged by contactor 35 when contact carrier 34 is in one of the operative switch positions as illustrated, for example, in Fig. 3, springs 36 maintaining a sufficient contact pressure between contactor 35 and the pair of stationary contacts 38^d, 41^a bridged by it. In this position a path of electrical conductivity is established from terminal member 41^b through collector ring 41, stationary contact 41^a, bridging contactor 35, stationary contact 38^d to terminal portion 38^b.

As will be apparent, rotary movement of contact carrier 34 as a function of movement of the snap action mechanism hereinbefore described from one operative switch position to the next, moves bridging contactor 35 rapidly out of engagement with stationary contacts 38^d and 41^a, the circuit therefore being broken at two points, which feature together with the snap movement heretofore described tends to minimize arcing of the contacts. This tendency to minimize arcing is further aided by virtue of the relationship of contact carrier 34 with mating shoulders 32^f and 37^e on base sections 32 and 37 respectively; this relation being such that as bridging contactor 35 reaches a point midway between any two operative switch positions it is substantially isolated by insulation material

from any current carrying parts, the adjacent portions of cylindrical portion 34^a of contact carrier 34 having rotated to meet shoulders 32^a and 37^a and flange portion 34^b having similarly rotated in its guideway formed by the top and bottom surfaces of said shoulders 31^a and 37^a respectively. Thus any arc which may have developed between bridging contactor 35 and either of the stationary contacts 41^a or 38^b is effectively cut off.

As will be apparent from inspection of Fig. 4, when bridging contactor 35 is in the operative switch position illustrated therein i. e. opposite terminal member 41^b, no electrical connection is made, thereby providing the switch with an "off" position if desired.

It will be obvious to those skilled in the art that in addition to the various commutation characteristics afforded by the flexibility of the number of operative switch positions and/or the number of poles provided as hereinbefore described, additional commutation combinations may be attained by provision of one or more additional combined stationary contact and terminal members 38 and/or addition of one or more additional contactors 35 in openings 34^c in contact carrier 34, as shown, for example, in Fig. 12, wherein is illustrated a switch having four combined contact and terminal members 38 and three contactors 35, it being obvious to those skilled in the art that said contactors 35 might be spaced in other arrangements than that illustrated.

Fig. 12 additionally illustrates a further variation in that collector ring 41 is shown with an additional terminal member 41^b. A still further commutation characteristic may be provided by breaking collector ring 41 into two or more segments as illustrated, for example, at 141^a, 141^b in Fig. 13, each segment being provided with a terminal member 41^b. From the foregoing, it will be apparent that the invention embodied by the drawings provides a multitude of circuit commutation combinations which may be achieved by a minimum of simple parts which are easily and quickly interchanged, thereby affording a switch of great flexibility.

I claim:

1. In a rotary switch, a substantially cylindrical insulating contact carrier rotatable on its central axis, an insulating base for said contact carrier, said base having walls to form about said contact carrier a plurality of chambers, and cooperating switch contacts comprising a contactor on said carrier and contacts mounted in pairs in said chambers, said carrier having its contactor peripherally mounted thereon and having a peripheral flange projecting from a midpoint of said contactor, said chambers being formed to receive therein with a rotating clearance said flange and having their respective contacts disposed on opposite sides of said flange to be engaged by the portions of said contactor on opposite sides of said flange, said base and said insulating contact carrier being close fitting to minimize persistence of any arcing as said contactor leaves any of said chambers.

2. In a rotary switch, a substantially cylindrical insulating contact carrier rotatable on its central axis, an insulating base supporting said contact carrier, said base having walls to form about said contact carrier peripherally thereof a plurality of individual contact chambers, and cooperating switch contacts comprising a contactor on said carrier and contacts mounted in pairs

in said chambers, said carrier having its contactor peripherally mounted thereon and having a peripheral flange projecting from a midpoint of said contactor, said chambers being formed to receive therein with a rotating clearance said flange and having their respective contacts disposed on opposite sides of said flange to be engaged by the portions of said contactor on opposite sides of said flange, said base and said insulating contact carrier being close fitting to minimize persistence of any arcing as said contactor leaves any of said chambers.

3. In a rotary electric switch, an actuating mechanism having a rotary actuated part, a substantially cylindrical insulating contact carrier rotatable on its central axis by said actuated part of said actuating mechanism, an insulating base supporting in coacting relation said mechanism and contact carrier, said base having walls forming about said contact carrier peripherally thereof a plurality of chambers, and cooperating switch contacts comprising at least one spring biased contactor on said carrier and contacts mounted in pairs in said chambers, said carrier having a plurality of peripheral recesses equally spaced from and about its center each for removable mounting therein of one such contactor in a parallel relation to its axis of rotation and said carrier having an encircling peripheral flange projecting from a midpoint of said contactor, said chambers being formed to receive therein with a rotating clearance said flange and having their respective contacts disposed on opposite sides of said flange to be engaged by the portions of said contactor on opposite sides of said flange, said base and said insulating contact carrier being close fitting to minimize persistence of any arc as said contactor leaves any of said chambers.

4. In a rotary electric switch, a snap acting actuating mechanism having a rotary actuated part, a substantially cylindrical insulating contact carrier rotatable on its central axis by said actuated part of said actuating mechanism, an insulating base supporting in coacting relation said mechanism and contact carrier, said base having walls forming about said contact carrier peripherally thereof a plurality of chambers each being open adjacent said carrier, and cooperating switch contacts comprising a contactor on said carrier and contacts mounted in pairs in said chambers, said carrier having its contactor mounted peripherally thereon in a parallel relation to its axis of rotation and having a peripheral flange projecting from a midpoint of said contactor, said chambers being formed to receive therein with a rotating clearance said flange and having their respective contacts disposed on opposite sides of said flange to be engaged by the portions of said contactor on opposite sides of said flange, one of each of said pairs of contacts comprising an upturned edge of a collector ring having at least one terminal portion.

5. In a rotary electric switch, a snap acting actuating mechanism having a rotary actuated part, a substantially cylindrical insulating contact carrier rotatable on its central axis by said actuated part of said actuating mechanism, said carrier having a contactor mounted peripherally thereon in a parallel relation to its axis of rotation and having a peripheral flange projecting laterally from a midpoint of said contactor, an insulating base supporting in coacting relation said mechanism and contact carrier, said base comprising a pair of base sections having walls

adapted to mate on a plane extending through said flange at a right angle to the central axis of said carrier, said base sections jointly forming an enclosure for said carrier and jointly forming peripherally thereof a plurality of chambers adapted to receive therein with a rotating clearance said flange, and a pair of contacts mounted in said chambers on opposite sides of said flange to be engaged by the portions of said contactor on opposite sides of said flange, said base and said insulating contact carrier being close fitting to minimize persistence of any arcing as said contactor leaves any of said chambers.

6. In a rotary electric switch, a snap acting actuating mechanism having a rotary actuated part, a substantially cylindrical insulating contact carrier rotatable on its central axis by said actuated part of said actuating mechanism, said carrier having a contactor mounted peripherally thereon in a parallel relation to its axis of rotation and having a peripheral flange projecting laterally from a midpoint of said contactor, a first insulating base section supporting said mechanism, a second base section adapted to mate with the first transversely of the axis of said carrier to house said carrier removably, said base sections having walls jointly forming peripherally of said carrier a plurality of chambers adapted to receive therein with a rotating clearance said flange, a pair of contacts mounted in one of said chambers on opposite sides of said flange to be engaged by the portions of said contactor on opposite sides of said flange, and a third base section adapted to be interposed between and to mate with said first and second base sections to provide separate housings, each of the character aforesaid, for two of said carriers and their cooperating contacts.

7. In a rotary electric switch, an actuating mechanism having a rotary actuated part, a plurality of substantially cylindrical contact carriers rotatable on a common central axis by said actuated part of said actuating mechanism, each of said carriers having a contactor mounted peripherally therein in a parallel relation to its axis of rotation and having a peripheral flange projecting laterally from a midpoint of said contactor, an insulating base supporting in coacting relation said mechanism and contact carriers and being divided transversely of the axis of said carriers into a plurality of sections, each two adjacent sections housing removably one of said carriers and having recessed mating walls jointly forming about the respective contact carrier peripherally thereof a plurality of chambers adapted to receive therein with a rotating clearance the flange of the carrier, and contacts mounted in pairs in at least some of said chambers, the contacts of each pair being spaced to receive therebetween the carrier flange accommodated by the respective chamber and being engageable for bridging by a contactor of the respective carrier.

8. In a rotary electric switch, an actuating mechanism having a rotary actuated part, a plurality of substantially cylindrical contact carriers rotatable on a common central axis by said actuated part of said actuating mechanism, each of said carriers having a contactor mounted peripherally therein in a parallel relation to its axis of rotation and having a peripheral flange projecting laterally from a midpoint of said contactor, an insulating base supporting in coacting relation said mechanism and contact carriers and

being divided transversely of the axis of said carriers into a plurality of sections, each two adjacent sections housing removably one of said carriers and having recessed mating walls jointly forming about the respective contact carrier peripherally thereof a plurality of chambers adapted to receive therein with a rotating clearance the flange of the carrier, and contacts mounted in pairs in at least some of said chambers, the contacts of each pair being spaced to receive therebetween the carrier flange accommodated by the respective chamber and being engageable for bridging by a contactor of the respective carrier, said contact carriers being interchangeable in respect of the base sections.

9. In a rotary electric switch, an actuating mechanism having a rotary actuated part, a plurality of substantially cylindrical contact carriers rotatable on a common central axis by said actuated part of said actuating mechanism, each of said carriers having a contactor mounted peripherally therein in a parallel relation to its axis of rotation and having a peripheral flange projecting laterally from a midpoint of said contactor, an insulating base supporting in coacting relation said mechanism and contact carriers and being divided transversely of the axis of said carriers into a plurality of sections, each two adjacent sections housing removably one of said carriers and having recessed mating walls jointly forming about the respective contact carrier peripherally thereof a plurality of chambers adapted to receive therein with a rotating clearance the flange of the carrier, and contacts mounted in pairs in at least some of said chambers, the contacts of each pair being spaced to receive therebetween the carrier flange accommodated by the respective chamber and being engageable for bridging by a contactor of the respective carrier, said contact carriers being interchangeable in respect of the base sections, and each intermediate base section having one side adapted to mate with one end base section and its other side adapted to mate with the other end base section to form with either end base section a carrier housing of the character aforesaid.

10. In a rotary electric switch, an actuating mechanism having a rotary actuated part, a substantially cylindrical insulating contact carrier concentrically mounted on said actuated part, said carrier having an integral relatively thin centrally positioned insulating flange laterally extending from its outer periphery, a bridging contactor resiliently mounted in said carrier adjacent said flange in parallel relation to its axis of rotation and being limited in outward radial displacement thereby, said contactor having contact portions extending above and below said flange, an insulating housing having interior portions which cooperate with said flange to provide a plurality of substantially isolated individual upper and lower contact chambers positioned along the outer periphery of said carrier and pairs of stationary contacts contained in at least some of said upper and lower chambers for bridging engagement by said bridging contactor, whereby the arcing occurring between pairs of engaging contacts is substantially isolated for rapid extinguishment when said contactor is moved out of engagement therewith.

11. As an article of manufacture, a contactor carrier assembly comprising a cylindrical insulating body portion for rotation on its central axis, said body portion having a contactor receiving recess in its periphery extending parallel to said

axis, a relatively thin integral peripheral insulating flange extending across the middle portion of said recess, a contactor removably mounted in said carrier recess with its contact portions exposed on opposite sides of said flange for tangential engagement with stationary contacts, said contactor also being limited in outward radial displacement by said flange, and a spring positioned within said recess and engaging said contactor to bias the latter outwardly into abutting relationship with said flange.

12. As an article of manufacture, a unitary molded insulating contactor carrier comprising a cylindrical body portion for rotation about its axis, said body portion having a plurality of individual contactor receiving recesses in its outer periphery, said recesses extending in a plane parallel to said axis, and an integral relatively thin substantially circular flange on the periphery of said body portion intermediate the ends thereof, said flange having notches in its inner periphery opposite said contactor receiving recesses whereby contactors located within said recesses may project radially outward a predetermined distance.

13. As an article of manufacture, a bridging contactor assembly, for use in an insulating contact carrier of the type wherein the contactor is resiliently retained within a recess and is limited in outward movement by an insulating flange extending across the face of said recess, comprising

30

a metal member of U-shape in transverse cross section and of good electrical conductivity, said metal member having a front contact portion and parallel side portions, said side portions having 5 alined notches extending throughout the depth of the former intermediate the ends thereof, and a coiled compression spring of a diameter to afford a snug fit thereof between the innermost edges of the walls of said notches, whereby said spring is restrained against lateral displacement in any direction relatively to said contactor.

10 14. A contactor assembly as in claim 13, wherein the diameter of the spring is no greater than the overall width of the metal member.

15 ALVIN W. KRIEGER.
